US0D1065012S

(12) **United States Design Patent** (10) Patent No.: **US D1,065,012 S**
(45) Date of Patent: ** Mar. 4, 2025

(54) **MOUNT FOR ROOFTOP ARTICLE
INSTALLATION**

(71) Applicant: **Yanegijutsukenkyo Co., Ltd.**,
Takahama (JP)

(72) Inventor: **Takayoshi Yamanaka**, Takahama (JP)

(73) Assignee: **YANEGIJUTSUKENKYUJO CO.,
LTD**, Takahama (JP)

(**) Term: **15 Years**

(21) Appl. No.: **29/885,755**

(22) Filed: **Feb. 28, 2023**

(51) LOC (15) Cl. **08-05**

(52) U.S. Cl.

USPC **D8/354**

(57) **CLAIM**

The ornamental design for a mount for rooftop article installation, as shown and described.

DESCRIPTION

FIG. 1 is a front elevational view of a mount for rooftop article installation, showing my new design, a rear elevational view being identical thereto;

FIG. 2 is a top plan view thereof, a bottom plan view being symmetrical therewith;

FIG. 3 is a right side elevational view thereof, a left side elevational view being identical thereto;

FIG. 4 is a sectional view taken along line 4-4 of FIG. 2; and,

FIG. 5 is a perspective view thereof.

The article is a mount for installing a rooftop article such as a clamp for holding a pipe on rooftop.

1 Claim, 5 Drawing Sheets
